HYDRAULIC VISE

Warren J. Stuckley, Brawley, Calif.

Application October 24, 1941, Serial No. 416,427

2 Claims. (Cl. 81—17)

The present invention is directed to improvements in fluid operated vises, either liquid or gas.

The primary object of the invention is to provide a vise so constructed that upon operating the means for controlling the actuating fluid the movable jaw will be moved and caused to clamp the work between the fixed and movable jaw with such force that any danger of the work slipping or becoming accidentally disengaged from between the jaws is positively prevented.

Another object of the invention is to provide a vise of this type constructed in such manner that the body of the vise may be rotated to various positions to enable the operator to place the work between the jaws and remove the same therefrom in any position he may be standing.

Still another object of the invention is to provide a vise wherein the piston rod and its head is maintained in fixed position, but the rod or tube in which the head is mounted is freely movable with the movable jaw, which places the piston and rod under tension instead of compression, as in the usual type of air or hydraulic vises.

With these and other objects in view, this invention resides in the novel features of construction, formation, combination and arrangement of parts to be hereinafter more fully described and claimed, and illustrated in the accompanying drawings, in which:

Figure 1 is a side view;

Figure 2 is an end view, on line 2—2 of Figure 1;

Figure 3 is a side view, the jaws being open;

Figure 4 is a longitudinal sectional view, the jaws open;

Figure 5 is a similar view, the jaws closed.

Figure 6 is an enlarged sectional view of the piston head connection.

Figure 7 is a sectional view on line 7—7 of Figure 6.

Referring to the drawings, 1 designates a stand or bench, and upon which is mounted the vise.

Bolted upon the top of the stand 1 is a supporting plate 2, in which is formed a bearing 3, and mounted in the bearing is a plug 4, said plug having upon its upper end a threaded extension 5. Extending through the plug and extension is a fluid conducting passage 6, the purpose of which will later appear.

The vise includes a body 7 in which is formed a threaded opening 8, and in which the extension 5 is engaged so that the vise may be rotated, as desired, upon the plate 2 manually.

The body is formed with a fixed jaw 9, and is

further provided with a bearing 10, said bearing being aligned with the cylinder 11 extending from the body.

The movable jaw 12 comprises a stem 13 adapted for sliding movement in the bearing 10 and cylinder 11. In the stem 13 is a tube 14 having in its forward end a threaded plug 15, the stem 16 of which extends from the jaw 12 and has threaded thereon a nut 17 serving to secure the stem to the jaw 12 and maintain the tube 14 in fixed relationship relative to the jaw 12 and stem 16.

The rear end of the tube 14 is closed by a cap 18 having a stuffing box 19 thereon. This stuffing box slidably engages the pressure fluid supplying pipe 19', the outer end of which is fixed to the cylinder 11 by jamb nuts 18'. Upon the inner end of the pipe 19 is fixed a piston head 20, there being ducts 21 formed in the pipe for the passage of fluid therefrom into the tube 14.

The outer end of the tube 19 is suitably fixed to a pipe assembly 22 in which is mounted a valve 23. The pipe 24 of the assembly passes through the body 7 and is connected to the plug 4 by a conventional type of swiveled coupling 24', and in fluid communication with the passage 6 so that fluid may pass therefrom, and through the pipe assembly into the tube 19.

Connected to the lower end of the plug 4 and communicating with the passage 6 thereof is a fluid conducting pipe 25. The pipe 25 leads from a hydraulic pump unit 26 of conventional form and includes a piston containing cylinder 27.

The cylinder 27 has pivotally connected thereto the inner end of a hand lever 28, there being a spring 29 connecting the lever 28 and stand 1. This spring serves to maintain the piston of the cylinder 27 in its uppermost position, and when the vise is at rest, the lower end of said spring is connected with the hand lever 28 at a point adjacent the piston rod 30.

A foot lever 31 is pivotally connected to the stand 1 and to the hand lever 28 by a rod and link 32 and 33, respectively.

Upon operating the hand lever 28 fluid, preferably oil, under pressure will pass from the pipe 25 into the pipe assembly 22, and from thence through the ducts 21 of the tube 19 into the cylinder 14. The fluid under pressure will then cause the jaw 12 to move toward the jaw 9 for clamping the work between said jaws. This is of course due to the fact that the piston 20 is stationary and the force of the fluid under pressure will exert pressure upon the cap 18 and piston head 20.

When the valve 23 is open the jaw 12 may be

moved outwardly by the operator upon grasping the same, and in this manner the work can be placed between the jaws and removed therefrom with ease.

A valve 38 is associated with the pump unit 26 to control the fluid therein.

If more leverage is desired a tubular handle 34' may be placed upon the hand lever 28, and, if desired the foot lever 31 may also be actuated.

Since the body 7 is rotatably engaged with the plug 4 and the pipe 24 is connected thereto by the coupling 24' the body may be rotated to any position to suit the convenience of the operator.

The body may be held in any of its adjusted positions by the conventional form of clamping post 39.

To prevent building up of pressure in the tube 14 in advance of the piston head 20, which would tend to retard the free sliding movement of the stem 13, bleed openings 36 and 37 are formed in the stem and tube, respectively.

What is claimed is:

1. A vise having a body having a bearing therein, a fixed jaw on the body, a slidable jaw having a stem movable in the bearing, a tube fixed within the stem, a pressure fluid conducting pipe fixed with the body and extending into the tube, a piston head in the tube and fixed to the pipe, said pipe having ducts therein, and means for forcing fluid under pressure through the pipe and from the ducts into the tube between the head and one end of the tube.

2. A vise comprising a fixed and a movable jaw, the movable jaw including a hollow stem slidable in the fixed jaw, a piston head in the stem, a fluid conducting pipe fixed relative to the fixed jaw and extending into the stem and fixed to the piston head, said pipe having ducts therein, and means for forcing pressure fluid under pressure through the pipe and from the ducts into the stem between the piston head and one end of the stem.

WARREN J. STUCKLEY.
